UNITED STATES PATENT OFFICE.

HARRY ARTHUR FOOTHORAP, OF HARRISBURG, PENNSYLVANIA, ASSIGNOR TO
ELLIOTT-FISHER COMPANY, OF HARRISBURG, PENNSYLVANIA, A CORPOR-
ATION OF DELAWARE.

TYPE-WRITING MACHINE.

1,251,361.

Specification of Letters Patent. Patented Dec. 25, 1917.

Application filed December 16, 1914. Serial No. 877,579.

To all whom it may concern:

Be it known that I, HARRY ARTHUR FOOTHORAP, a citizen of the United States of America, residing at Harrisburg, in the county of 5 Dauphin and State of Pennsylvania, have invented certain new and useful Improvements in Type-Writing Machines, of which the following is a specification.

This invention relates to typewriting machines of that class which is characterized by a flat platen and downwardly acting printing mechanism. More particularly, the invention relates to the printing mechanism comprehending that group of elements between and intimately associated with the keys and type bars.

An object of the invention, considered generally, is to produce a type action capable of being operated by minimum of power 10 economically applied to secure a smooth, snappy type action with a light touch and without objectionable lost motion or interference of the parts resulting from rebound or other causes.

Another object of the invention is to secure accelerated movement of the type bar during the printing stroke, correspondingly quick return movement of the bar after the printing impact and automatic locking of 20 the bar against rebound in a printing mechanism adapted for use in what is known as a visible writing or open segment machine of the class under consideration.

Another object of the invention is to so 35 construct the printing mechanism of the specified character that, while the type bars and the operating connections thereof are arranged in substantially semi-circular or open segment formation, the key levers may 40 be provided with a common fulcrum bar.

Still another object of the invention is to divide the printing mechanism into a series of assemblage units capable of separate grouping or assemblage as units and of being quickly, conveniently and accurately 45 connected up with the other units for economy of manufacture, assemblage and repair.

Subordinate features of the invention reside in the construction and arrangement 50 of the mounting of the various elements and in the character and arrangement of the connections between the type bars and the keys.

To the accomplishment of the recited objects and others which will more fully ap-

pear hereinafter, the invention resides in the 55 construction and arrangement of parts to be presently described, illustrated in the accompanying drawings and defined in the appended claims.

In the accompanying drawings:—

Figure 1 is a vertical section through the carriage, frame and platen of an Elliott-Fisher Billing Machine equipped with printing mechanism constructed in accordance with my invention but certain of the parts 60 and portions of others being omitted to avoid confusion.

Fig. 2 is a top plan view of a type bar hanger ring with certain of the type bar 65 hangers in place and others omitted.

Fig. 3 is a bottom plan view of the subject matter of Fig. 2.

Fig. 4 is a plan view showing the arrangement and relation of the sub-levers and type bars and the method of grouping the levers 75 on the deck.

Fig. 5 is a plan view showing the arrangement of the key levers and the relation of the push bar connections.

Fig. 6 is a sectional view on an enlarged 80 scale of a pair of type bars and their mountings and the major portions of their operative connections, one of the bars being shown in the printing position but broken away and the other being shown in normal position.

Fig. 7 is a detail view of an upper type bar hanger.

Fig. 8 is a similar view of a lower type 90 bar hanger.

Fig. 9 is a detail view of one of the push rods.

Fig. 10 is a detail section of the fulcrum bar and its mounting.

Fig. 11 is a detail perspective of the ro- 95 tatable bushing of the fulcrum bar.

Fig. 12 is a detail view of the fulcrum bar, with its middle portion broken away, and

Fig. 13 is a perspective view of the ma- 100 chine with portions of the line space frame and platen broken away.

The machine under consideration embodies a flat platen 1 for the work element or sheet and tracks or guides 2 disposed longitudinally of the platen to support the movable 105 machine frame 3, sometimes called a line space frame.

Mounted to travel on the frame 3 in a di-

rection transverse to the platen or lengthwise of the line of writing is a carriage 4 preferably mounted on front and rear rolls 5 and 6 and having guide rollers 7, two of which are shown in Fig. 1. It is on the carriage 4 that the printing mechanism is mounted and it may obviously be advanced for line spacing by the advance of the frame 3 or fed step by step for letter spacing by the movement of the carriage across the frame.

The three primary elements of the carriage 4 are the type bar hanger ring 8, which, for brevity, will be called the type ring, the sublever supporting deck 9, to be referred to as the deck, and the casing 10, the upper part of which is in the form of a cover plate 11.

At its front, the deck 9 is supported by the carriage corner posts 12 to which the journals 13 of the front rollers 5 are attached and these posts extend downwardly to a plane above the top of the frame 3 to support the type ring 8 which is located comparatively close to the platen. The ring 8 is of arcuate or segmental shape, as shown in Fig. 2, and its rear portion is supported by a pair of type ring posts 14 attached to the deck 9. The rear carriage rolls 6 are located immediately below the deck having journals 15 carried by brackets 16 secured to the under side of the deck, as shown in Fig. 1. By reference to Fig. 4, it will be seen that the deck 9 is in the form of a rectangular plate which may be and probably is of aluminum and cut out to give its front edge a segmental or arcuate formation substantially corresponding to that of the type ring 8 but of slightly greater diameter than the inner edge of said ring in order that the ring may extend slightly nearer the axis of the arc or segment, which defines the printing point of the machine. (See Fig. 4.)

That portion of the carriage lying below the deck and between the corner posts 12 is free and unobstructed and as the type ring is of open segment form, the printing point is fully exposed to the view of the operator and this freedom of vision is further enhanced by the open formation of the front 50 of the deck and the arched form of the front plate 10 of the carriage casing.

Generally speaking, the type ring 8 is designed to support in compact assemblage, the type bar hangers, type bars and buffer 55 ring. The deck is designed to support the sub-lever system constituting part of the operating connections between the keys and type bars and the carriage casing, or a single fulerum bar located therein, serves to 60 support a system of key levers.

In order to assemble the requisite number of type bars in the comparatively small space allotted to their mounting and at the same time to secure wide bearings conducive 65 to general stability and the maintenance of

proper alinement, it is necessary to mount the bars in staggered relation. To attain this end and at the same time avoid such crowding of the parts as will interfere with rapid assemblage and repair, the type bar 70 hangers are divided into two sets or series mounted respectively on the upper and under sides of the type ring 8, as best shown in Fig. 6. The lower hangers 17 have the form of plates bent to approximate U-shape, 75 disposed horizontally and having their extremities bent upwardly to form bearing lugs 18 having apertures 19 for the reception of the journals 20 of the type bars 21. The bearing ends of the hangers 17 are 80 flared somewhat, as shown in Fig. 8, to accommodate the hubs 22 of the bars. Below the lugs 18, the sides of the hanger are connected and held rigidly in proper relation by a bolt 23 and somewhat nearer the outer end of the hanger is interposed a spacer 24. The lower hangers are secured to the under side of the type ring 8 by headed screws 25 passed upwardly through the double end of the hanger and threaded into suitable openings 26 formed in the ring 8 adjacent to its inner edge and equidistantly spaced apart. Interposed between the head of the screw 25 and the hanger is a washer plate 27, each of these plates being of sufficient length to 95 serve three hangers, as shown in Fig. 3.

The second set or series of hangers, known as the upper type bar hangers 28, are assembled on the upper side of the type ring 8 and are arranged in alternation with the lower hangers 17. These upper hangers 28 are constructed in a manner similar to the hangers 17 but are of slightly different design, being somewhat longer and their ends being bent downwardly instead of upwardly 105 to form bearing lugs 29 for the outside set or series of type bars 30. The lugs 29 are formed with openings 31 for the journals 32 of the type bars 30 and the ends of the lugs are connected by a bolt 33 similar in function to the bolt 23 of the lower hangers. Also the upper hangers are provided with spacers 34 corresponding to the spacers 24 of the hangers 17. The securing bolts 35 for the upper hangers are passed upwardly 115 through openings 36 in the type ring and, after passing through the double ends of the upper hangers, are screwed into nut plates 37 each of which spans three bolts and constitutes what is in effect a nut common to 120 all of them.

The described arrangement of the securing devices for the upper and lower sets or series of hangers locates the heads of both sets of securing bolts below the type ring so 125 that when the carriage is tilted to give access to its under side, all the bolts are accessible to facilitate both assembling and repair.

The described arrangement of the upper 130

and lower hangers disposes them in alternation, as already stated, and locates the axes of the inner and outer sets of type bars in nearly the same horizontal plane and in 5 two concentric arcuate series of different radius. Thus ample room is afforded for each type bar bearing but the type bars, nevertheless are grouped in exceedingly close formation so that a comparatively large 10 number can be mounted in the limited space available.

In Fig. 2, the relation of the type bar hangers will be clearly seen. At the left hand end of the type ring, three lower hangers and the adjacent upper hangers are 15 shown in plan view. Next, I have shown several upper hangers with the lower hangers omitted and further along are shown four lower hangers with the upper hangers 20 omitted. It will be noted that the lower hangers, by reason of the expanded form of their inner ends, approach each other closely and afford wide bearings for the bars. The same thing is true of the upper bearings but 25 when we consider the relation of the upper and lower bearings, we find that the comparatively narrow spaces between the bearings of one set come directly opposite the medial lines of the hangers of the other set, 30 the close spacing being thus made possible because the intervals left between the hangers of one set need only be sufficient to accommodate the comparatively thin type bars of the other set.

35 We have now described the mounting of the type bars on the type ring and it is next in order to consider the operating connections which, as already stated, are largely supported from the deck 9. Suspended 40 from the deck 9 and adjacent to its inner edge is a series of bifurcated bell crank hangers 38 in each of which is fulcrumed a bell crank lever 39 of the third class connected at its lower end to a turn buckle 40 threaded upon a draw wire 41, the lower end of which is formed with a hook 42 which engages an opening in the tail piece 43 with which each type bar is provided. At a point intermediate of and in angular relation with 45 the fulcrum 39^a of the bell crank 39, and the connection 40^a of said bell crank with the draw wire 41, said bell crank is connected as at 44^a to the lower end of what is known as the upper draw wire 44 formed with 50 hooks at its opposite ends for engagement with the bell crank 39 and the front end of a sub-lever 45 fulcrumed in a post 46 from which a threaded shank 47 extends downwardly through the deck 9 and secured by a 55 nut 48 screwed upon the lower end of the shank 47 and against the under side of the deck.

60 Inasmuch as all the key levers are fulcrumed in rear of the type basket and in a space only slightly wider than the same, the

fulcrum posts 46 are so arranged on the deck 9 that the sub-levers will have a generally convergent relation, in a rearward direction, except at the sides of the arc where so many of the levers bear an almost tangential relation to the arcuate series of upper draw wires, that it becomes necessary to give these levers a generally convergent relation toward the front in order that their rear ends may be properly disposed for connection to the equi-distantly spaced key levers, 70 hereafter referred to. Even this expedient, however, is not adequate to properly dispose the sub-levers at the side, for connection with the upper draw wires and the key levers, 75 without danger of interference. It becomes further necessary to impart an inward curve in varying degree to the front ends of these side levers, as clearly shown in Fig. 4, and to mount alternate levers in different horizontal planes. Thus, as will be seen in Fig. 1, 80 four of the sub-levers at each side of the series are provided with elevated fulcrum posts which elevate these levers sufficiently above the adjacent levers to avoid possible interference. For convenience, the elevated levers may be designated by 45^a and their fulcrum posts 46^a. The rear ends of the sub-levers 45 are connected to the hooked lower 85 ends of push rods 49 having at their upper 90 ends turn buckles 50 pivotally connected to key levers 51 arranged in a horizontal bank or series in the upper portion of the carriage casing 10. The entire series of levers 51 are swung from a single fulcrum bar 52 95 mounted in rotatable bushings 53 in the sides of the carriage casing and held against endwise movement by locking screw 54. The key levers 51 have bifurcated rear ends 55 defined by open bearings 56 substantially 100 conforming to the diameter of the fulcrum bar 52 and the opening or throat 57 of the bearing being somewhat restricted to conform to the minor diameter of the fulcrum bar which, as shown in Fig. 1, is flattened on 105 opposite sides. By turning the fulcrum bar 52 so that its flat sides will be disposed horizontally, the key levers may be readily slipped thereon and then locked by the simple 110 act of turning the fulcrum bar to present its major diameter perpendicular to the throat 57. Immediately above the fulcrum bar 52 the levers are spaced and guided by a comb plate 58 having a flange 59 which serves as a fixed point of attachment for the 115 upper ends of the key lever retracting 120 springs 60. A similar comb plate 61 serves to guide the front ends of the key levers.

The upper ends of the type bars when in normal position rest against a leather or 125 other suitable buffer 62 carried by a buffer ring 63 of tubular form, bent to produce an arcuate rest for the type bars and to provide supporting posts 64 spread somewhat, as shown in Fig. 4, and having their lower 130

ends secured to the front ends of the type ring. The buffer ring is supported at its rear side by a rear buffer ring post 65 screwed to the ring and to the type ring, as shown in 5 Figs. 1 and 4. The lower end of the post 65 is deflected in order to remove it from interfering relation with the type bar hangers and adjacent parts. Conforming to the outer side of the buffer and secured thereto 10 by screws, as shown in Fig. 4, is a spring plate 66 provided with apertures for the attachment of type bar retracting springs 67, the lower ends of which are secured to type bar spring yokes 68 pivotally connected to 15 the type bars adjacent to their lower ends.

The foregoing constitutes a full description of the construction of that part of the machine with which the present application is concerned and particular attention is now 20 directed to the operation of the type action. Obviously depression of one of the keys 51^a at the front ends of the key levers 51 will swing a sub-lever 45 through the intermediate push rod 49. As the front end of the sub- 25 lever rises a bell crank lever 39 will be swung through the medium of the upper draw wire 44 and will in turn elevate the tail piece of a key lever through the medium of the lower draw wire 41. In this way the type 30 bar will be swung down to the printing point from which it will quickly revert to normal position under the retractile force of the springs 60 and 67 as soon as pressure on the key is relieved.

35 It will be noted that the printing stroke of the type bar is accomplished by an accelerated movement thereof. This is due to the fact that the fulcrum, resistance and power points of the levers 33 are disposed 40 in such angular formation that the leverage exerted upon the type bar by its operating connections will be greatest at the beginning of the stroke and gradually diminished, the result being the slow but easy start of the 45 type bar and accelerated movement thereof as it approaches the printing point. Thus the greatest leverage is exerted while the inertia of the parts is being overcome and as the leverage decreases the effect of such 50 decrease, so far as increased resistance to the finger of the operator is concerned, is offset by the momentum of the type bar. This acceleration is due to the fact that during the initial movement of the parts, the 55 connection 44^a of the lever 39 will move through a vertical arc while the connection 40^a will move through a more nearly horizontal arc. The movement imparted to the lever 39 is lengthwise of the vertical arc 60 while the movement transmitted to the tail piece of the type bar is only equivalent to the vertical rise of the connection 40 as it passes through the horizontal arc. As the movement continues, however, the connection 65 40 begins to traverse a more nearly ver-

tical arc while the connection 44^a continues its substantially vertical movement. Thus, after the initial movement of the parts, the variation between the movement imparted to the lever 39 and the movement transmitted to the tail piece of the type bar is decreased and the speed of the type bar is relatively increased. Thus, in consequence of this relation of the connections, a very light touch is secured and a quick, snappy movement is imparted to the type bar. In addition to the light touch and snappy action of the bar, the described arrangement of the operating connections has another useful function. It entirely eliminates any material rebound of the type bar after retraction, which rebound might otherwise result in interference between two immediately adjacent bars operated in quick succession. This locking against rebound results from the fact that in the normal position of the type bar, the connection 40^a is substantially in line with the fulcrum 39^a and the connection between the lower draw wire and the tail piece of the type bar. 90 Therefore, when the bar returns, its rebound is prevented by the rigid abutment formed by the lower draw wire 41 and the lever 39. This abutment, however, is of the general nature of a toggle and, while resisting the endwise thrust caused by any tendency of the bar to rebound, is readily broken or operated in a sidewise direction when pressure is exerted on the key.

It is thought that from the foregoing, the construction and operation of the described embodiment of my invention will be clearly understood, but I wish distinctly to reserve the right to effect such changes, modifications or variations of the illustrated structure as may fall fairly within the scope of the protection prayed.

What I claim is:—

1. In a typewriter, the combination with a type ring and a radially disposed series of normally vertical type bars carried thereby and having typeheads, of a deck located in a horizontal plane below the type heads, a series of key levers disposed in a plane above the type bars and having a common axis of movement at their rear ends, and operating connections between the key levers and the type bars, said operating connections including sub-levers mounted on the deck.

2. In a typewriter, the combination with a type ring of a forwardly opening segmental form, of a deck located above the type ring and having its front edge of forwardly opening arcuate form, a forwardly opening arcuate series of normally vertical, radially disposed type bars carried by the type ring and normally extended above the deck, a series of key levers having keys defining a key board at the front of the ma-

chine and over the type basket and having a common axis of movement at their rear ends, a series of sub-levers carried by the deck and connections between the key levers 5 and the sub-levers and between the sub-levers and the type bars.

3. In a typewriter, the combination with a type basket comprising a type ring and a forwardly opening arcuate series of normally vertical, radially disposed type bars, of a deck located above the type ring, sub-levers mounted on the deck and all extending in the same general direction, to wit, from front to rear of the machine, operating 10 connections between the front ends of the sub-levers and the several type bars, a series of key levers mounted above the sub-levers and swung from a common axis and connections between the rear ends of the 15 sub-levers and the key levers.

4. In a typewriter, the combination with a forwardly opening segmental series of radially disposed normally vertical type bars forming a type segment or basket, of 20 sub-levers corresponding in number to the type bars and having their front ends arranged in a series substantially conforming to the curvature of the type segment, all of said levers extending toward the rear of the 25 machine and certain of said levers being in crossing relation to each other, a series of key levers each operatively connected to a sub-lever and connections between the sub-levers and the type bars.

5. In a typewriter, the combination with a forwardly opening segmental series of radially disposed, normally vertical type bars, of sub-levers extending from front to rear of the typewriter and having their front ends 40 disposed in a segmental series substantially conforming to the type segment, certain of the sub-levers at opposite ends of the series being mounted in different horizontal planes to prevent interference, a series of key levers 45 mounted to swing from a common fulcrum at the rear side of the machine and suitable connections between the two sets of levers and between the sub-levers and the type bars.

6. In a typewriter, the combination with a forwardly opening segmental series of radially disposed, normally vertical type bars, of a deck located in a horizontal plane below the upper ends of the type bars, a series of 55 sub-levers mounted on the deck and extended rearwardly from the type segment, levers at the opposite sides of the type segment having their front ends deflected toward the type segment and alternate levers 60 at the sides of the segment being mounted in a higher plane than the adjacent levers and bearing a crossing relation thereto, key levers located in a plane above the sub-levers and mounted to swing from a common axis 65 at the rear ends of the key levers and suit-

able connections between the key levers and the sub-levers and between the sub-levers and the type bars.

7. In a typewriter, the combination with a forwardly opening segmental series of radially disposed, normally vertical type bars, of a deck, a series of key levers above the type bars and operating connections between the key levers and type bars, said connections including levers supported by the 70 deck and mounted both above and below the same.

8. In a typewriter, the combination with a forwardly opening segmental series of radially disposed, normally vertical type bars, 75 of a type ring supporting said bars, a series of key levers above the bars, a deck intermediate of the type ring and key levers, a series of radially disposed bell crank levers carried by the deck, connections between the 80 bell crank levers and the type bars, a series of sub-levers also carried by the deck and extended from front to rear of the typewriter, connections between the sub-levers and bell crank levers and connections between the 85 sub-levers and the key levers.

9. In a typewriter, the combination with a forwardly opening segmental series of radially disposed, normally vertical type bars, of a type ring supporting said bars, a deck, 90 a series of key levers mounted above the bars and swung from a common axis, a series of radially disposed bell crank levers carried by the deck, draw wires connecting the bell crank levers with the type bars, said draw 95 wires being in substantial alinement with the fulcrums of the bell crank levers in the normal position of the type bars to lock said type bars against rebound, a series of sub-levers also mounted on the deck and all extended from front to rear of the typewriter, connections between the sub-levers and the bell crank levers and other connections between the sub-levers and the key levers.

10. In a typewriter, the combination with an arcuate series of normally vertical type bars each having a tail piece, of a deck located in a plane above the tail pieces, an arcuate series of radially disposed hangers depending from the front edge of the deck, 110 bell crank levers mounted in the hangers, a draw wire connecting each bell crank lever with a tail piece and assuming a locking relation to the fulcrum of the bell crank lever to prevent rebound of the type bar from 115 normal position, fulcrum posts mounted on the deck at points removed from the front edge thereof, sub-levers fulcrumed in the posts and extended from front to rear of the machine, upper draw wires connecting 120 the front ends of the sub-levers to the bell crank levers, a series of parallel key levers fulcrumed on a common axis at their rear ends and push rods connecting the key levers with the sub-levers.

11. In a typewriter, the combination with a type hanger supporting ring, of upper and lower series of type hangers secured to the upper and lower sides of the ring in staggered relation, the bearing ends of adjacent hangers being deflected in opposite directions to dispose the type arm bearings in substantially the same horizontal plane and in the plane of the type ring.
- 10 12. In a typewriter, the combination with a type hanger supporting ring, of upper and lower series of radially disposed type hangers secured at their outer ends to the upper and lower sides of the type ring in staggered relation, the inner or bearing ends of each hanger being deflected toward the opposite side of the ring to bring all the type arm bearings in substantially the same horizontal plane and the inner end of each hanger being flared or widened beyond the sides of the two adjacent hangers.
- 15 13. In a typewriter, the combination with a type ring, a deck located above the same and having a segmental opening substantially conforming to the type ring, type bars carried by the type ring and extended above the deck, a carriage casing mounted above the deck and key levers mounted in the carriage casing and operatively connected to the type bars, the front wall of the carriage casing being arched across the front of the deck opening to expose the printing point to the view of the operator.
- 20 14. In a typewriter, the combination with a forwardly opening segmental type ring, of a forwardly opening segmental series of type bars carried by the ring, a deck supported above the type ring and having its front edge of forwardly opening segmental form, a carriage casing mounted above the deck and having a vertical front wall in the form of a horizontal arch spanning the front side of the arcuate opening in the deck to permit the printing point to be plainly viewed from a point above and in advance of the deck, and means mounted in the carriage casing for operating the type bars.
- 25 15. In a typewriter machine, the combination with a series of key levers having open bearings with constricted throats and a common fulcrum bar for said levers, said bar having a major diameter substantially corresponding to the diameter of the bearings and a minor diameter substantially corresponding to that of the constricted throat, rotatable bushings for the fulcrum bar and means for locking the bar against endwise movement.
- 30 16. In a typewriter, the combination with a type ring, a deck located above the same and having a segmental opening and a buffer ring above the deck, of type bars mounted on the type ring and extended above the deck to engage the buffer ring, a series of key levers located above the type bars, and operating connections between the type bars and key levers and carried in part by the deck.
- 35 17. In a typewriter, the combination with a forwardly opening segmental series of type bars, of a deck, a series of sub-levers mounted on the deck and extending from front to rear of the machine, alternate levers at the sides of the segment being mounted in a higher plane than the adjacent levers, and bearing a crossing relation thereto, key levers located in a plane above the sub-levers and mounted to swing from a common axis at the rear ends of the key levers, and suitable connections between the key levers and the sub-levers and between the sub-levers and the type bars.
- 40 18. In a typewriter, the combination with a forwardly opening segmental series of type bars, of a deck, a series of sub-levers mounted on the deck and extending from front to rear of the machine, alternate levers at the sides of the segment being mounted in a higher plane than the adjacent levers, and bearing a crossing relation thereto, key levers located in plane above the sub-levers, and suitable connections between the key levers and the sub-levers and between the sub-levers and the type bars.
- 45 19. In a typewriter, the combination with a type ring and a radially disposed series of normally vertical type bars carried thereby and having typeheads, of a deck located in a horizontal plane below the type heads, a series of key levers disposed in a plane above the type bars and having a common axis of movement at their rear ends, and operating connections between the key levers and the type bars, said operating connections including sub-levers mounted on the deck both above and below the same.
- 50 In testimony whereof I affix my signature in presence of two witnesses.
